UNITED STATES PATENT OFFICE.

AUGUST ERIE, OF MILWAUKEE, WISCONSIN.

SUBMARINE.

Application filed June 18, 1926. Serial No. 116,834.

This invention relates to certain new and useful improvements in submarines and has as an object the provision of a device whereby means of escape are provided in the event 5 the craft is disabled while submerged which means also provides a line of communication with the interior of the craft.

Many distressing and appalling accidents have occurred in the submarine navies of the 10 world when the machinery of the submarine has become disabled through collision or other means, due to the fact that no escape is provided for any one or more occupants of the disabled craft when the same is submerged and unable to rise to the surface. Therefore, this invention has as its primary object the provision of an improved appliance wherein an efficient means of escape from a disabled submarine craft is provided 15 which means establishes a line of communication with the interior of the disabled craft and is capable of being retracted into the craft to provide means of escape for the remaining persons.

Another object of this invention resides 20 in the provision of an improved appliance for submarines which is so designed and constructed as to be capable of affording a free release irrespective of the lie of the craft 25 on the bottom of the sea.

A further object of this invention resides 30 in the provision of an improved and efficient appliance of the character described which may be readily applied to submarines of all 35 types without in any wise impairing their normal operation.

Oftentimes submarines, upon being disabled, can be brought to the surface if a few pounds of additional air pressure can be obtained. Heretofore, this has been impossible with the craft disabled on the floor of the sea and this invention has as a further object the provision of an appliance of the character described whereby the release of 45 the appliance to the surface and its opening by the person therein affords means whereby the additional air required may be readily drawn into the craft to thus give it the buoyancy necessary to float it to the surface.

And a still further object of this invention resides in the provision of an improved appliance of the character described having improved release doors and means for operating the same.

With the above and other objects in view

which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawings, I have 60 illustrated one complete example of the physical embodiment of my invention constructed according to the best mode I have so far devised for the practical application of the principles thereof, and in which:

Figure 1 is a view, partly in section and partly in elevation, taken transversely through one section of a submarine craft embodying my invention, parts thereof being broken away and said view being taken on 70 the plane of the line 1—1 of Figure 2;

Figure 2 is a view, partly in section and partly in elevation, taken through Figure 1 on the plane of the line 2—2;

Figure 3 is a view taken transversely 80 through Figure 1 on the plane of the line 3—3;

Figure 4 is a fragmentary detail view, partly in section and partly in elevation, taken through Figure 2 on the plane of the 85 line 4—4 illustrating the means for securing the end cap or cover of the buoy, and

Figure 5 is a diagrammatic perspective view of a submarine illustrating the respective dispositions of more than one appliance to 90 a craft.

Referring now more particularly to the accompanying drawings, in which like numerals designate like parts throughout the several views, the numeral 5 designates a 95 submarine craft of any construction having a conventional hull or body portion 6, the interior of which is divided into an engine room, battery rooms, torpedo rooms and the like as is customary in craft of this kind 100 and located in one or more compartments and extending across the hull 6 and intersecting its axis is a tube or cylinder 7 having its ends closed by movable doors 8, to be later described. If desired, more than one 105 cylinder or tube 7 may be provided, as illustrated in Figure 5, in which event their axes are arranged at different angles with respect to each other so that irrespective of the craft's angle of repose, one cylinder in- 110

elines upwardly. As all the cylinders and appliances connected therewith are identical in construction, but one has been illustrated in detail and is hereinafter described.

5 Each door 8 is hinged to the hull, as at 9, and has an annular rib or bead 10 on its inner face fitting in a corresponding groove or channel 11 in the hull concentric with the cylinder and having a packing 12 therein 10 to insure a fluid tight joint when the same is locked by a pivoted catch member 13 cooperating with a locking recess 14 in the wall of the cylinder and door actuating mechanism 15, now about to be described.

15 Projected from the door 8 adjacent its hinge 9 is a fin 16 to the outer end of which one end 17 of a contractile spring 18 is secured, the other end 19 of the spring being secured to a rod 20 which is slidably but 20 non-rotatably mounted in the hull of the craft by a standard 21 and a stuffing box or packing gland 22 at the point the rod enters the interior of the craft at an enlarged or bulged portion 23 in the hull. The 25 outer portion of the rod 20 is preferably rectangular in cross section to cooperate with the standard 21 to prevent its rotation and the inner portion thereof is round where it enters the hull and has its extreme end 30 threaded, as at 24, to receive a worm wheel 25 mounted between a pair of spaced supports 26 secured in the enlarged portion 23 of the hull. A drive shaft 27 is journaled in the supports 26 at right angles to the 35 shaft 24 and carries a worm, not shown, meshing with the wheel 25 whereby rotation of the shaft 27 by a hand wheel 28 fixed thereto rotates the wheel 25 threading the end 24 of the shaft 20 therein, movement of 40 the shaft to the right with reference to Figure 1 disengaging the extreme outer end 29 of the rod from the fin 16 and causing the spring 18 to exert an opening pressure on the door and an opposite movement of the 45 rod engaging the end 29 of the same with the fin 16 to close the door 8.

An extension or lip 30 is formed on the portion of the door 8 diametrically opposed to the hinge 9 for engagement by a plunger 50 or rod 31 which is projectable through the hull of the craft at a packing gland or stuffing box 32 to exert an opening force on the door when it is desired to move the same to its open position. The plunger 31 passes 55 into the interior of the craft, exteriorly of the cylinder 7 and works in a cylinder 33, one end of which is connected with the interior through an elbow 34, there being a valve controlled by a hand wheel 35 located 60 therein. A piston 36 is mounted in the cylinder 33 and has the inner end of the rod 31 connected therewith, an expansile spring 37 at all times tending to urge the piston 36 65 into the cylinder 33 to hold the end of the rod 31 out of contact with the door lip 30.

The interior of the cylinder is communicable at each end with the outside through ducts 38 having control valves 39 therein so that the pressure of the water on the outside of the craft may be introduced into 70 the interior of the cylinder to assist in the opening of the door 8 through which egress is to be made. Upon the opening of any one of the valves 39, the pressure within the cylinder 7 equalizes with the outside 75 pressure and assuming wheel 28 has been rotated to retract rod 20, the door through which egress is to be made is initially opened by the adjacent plunger or rod 31, provided its valve 35 is open, due to the 80 increased area of the piston over that of the rod.

After the door has been initially opened by the plunger 31, the spring 18 exerts sufficient force to swing the door to its full open 85 position illustrated by dotted lines in Figure 1, thus permitting the escape from the chamber or cylinder 7 of the buoy 40 now about to be described.

The buoy 40 is in the form of a casing or 90 housing 41 of a diameter and length to receive at least one man and the ends thereof are closed by doors or caps 42. Each door or cap 42 is preferably of substantially 95 cone-shape and is hinged to the casing 41, as at 43, and has an annular flange or bead 44 cooperating with an annular packing recess in the end of the casing, the caps being secured closed by wing nuts 45 threaded on pivoted bolts 46 carried thereby and engageable between pairs of spaced lugs 47 formed on the casing adjacent the ends of the bolts. Cooperating with the wing nuts are a plurality of locking levers 48 secured to stub shafts 49 which are journaled in fluid tight bearings 50 in the caps or covers. The outer ends of the shafts 49 are squared, as at 51, and handle portions 52 are extended from the locking levers 48, thus providing means for locking the caps or covers closed, from the exterior of the housing as well as from the interior. A wrench 53 is engageable over the squared end of the shafts to facilitate the manipulation of the locking levers from the outside. 115 Suitable cam shaped locking lugs 54 are arranged to be engaged by the locking levers 48, as best illustrated in Figure 4. The caps 42 also have a plurality of lugs or 120 projections 55 formed thereon adjacent their peripheral edges to mount a platform 56 in the inverted cap and a port hole 57 of the usual type used in submarine constructions is likewise provided so that the occupant of the buoy may survey the surrounding area after the same has reached the surface in the manner later described.

The cylinder 7 has an entrance 58 leading to the interior of the craft and which is closed by a bulk head door 59 provided 125

with a packing joint 60 and removably secured in place by a series of locking levers 61 of a construction similar to the construction of the locking levers 48, on the 5 shafts 62 of which handle members 63 are formed to permit the operation of the levers from the inside of the submarine, the locking lug portions 64 of the levers working in inclined recesses 65 in the 10 wall of the passage 58.

A pair of concentric apertures 66 and 67 are formed in the opposite walls of the cylinder 7 adjacent each door 8 to removably mount the bearing members 68 and 69, respectively, of a drum shaft 70. The member 68 is in the form of a tapered bearing and the member 69 is in the form of a larger plate having a flange 71 which may be secured to the housing 7 by bolts or 20 other means 72 to cause the members 69 and 68 to have a snug fit in their apertures, which are preferably tapered.

The shaft 70 passes into the interior of the submarine through the plate member 25 69 and has a gear 73 splined thereon, with which a pinion 74 is meshed. The shaft 75 of the pinion is removably journaled in a bearing portion 76 mounted adjacent the opening 67 so that when the pinion is rotated by a crank 77 the shaft 70 rotates to wind or unwind a cable 78 on a drum 79 fixed to the shaft 70 to control the buoy. The cable is connected with the eye 80 of a threaded bolt 81 adjustable in the nose of 35 the lowermost cap. A bolt or shaft 81 is carried by each cap of the buoy and is passed through a stuffing box or packing gland 82 and threaded in a spider 83 secured in the cap, being extended or retracted by an operating wheel 84 on its inner end, as later described.

The drum 79, when its cable is wound thereon, is of a diameter less than the diameter of the opening 67 to permit the removal of the cable drum therethrough and its securement at either end of the tube 7 so that in the event the craft is so positioned on the bottom of the ocean that the normal 45 upper end of the cylinder 7 is lowermost, the drum 79 may be removed from the position illustrated in Figure 1 and mounted at the opposite end. This reverses the direction of the buoy and the cable 79 is connected with the other eye 80 by a snap or 50 readily detachable clevis device 85 and the openings 64 and 67, when not in use are closed by plates 86 and 87, respectively.

Also wound on the drum 79 and strung alongside the cable 78 is an air hose 88, 55 one end of which is connectible with the interior of the buoy through the lowermost cap by a coupling plug 89 threaded in an opening 90 in the cap. The opening 90 is closed by a removable plug 91 when the 60 same is uppermost, and the air hose 88 is

only connected with the lowermost cap, as illustrated. The other end of the air hose is connected in any manner with the interior of the shaft 70 which is tubular and the end of the shaft outwardly of the gear 73 70 is threaded, as at 91', to receive the coupling 92 of an air pipe 93 leading to an air pump, not shown. Telephone wires 94 leading to an instrument 95 normally mounted in the buoy and to an instrument 96 located within the craft are also preferably lead through the hose 88 to contacts 97 mounted on and insulated from the gear 73 and with which spring contacts 98 are engageable.

Assuming the craft equipped with my improved buoy becomes disabled, one of the occupants may be readily dispatched to the surface to display signs of distress. The seaman elected for this duty first enters the 85 cylinder 7 through the passage 58, releases the latch 13 of the uppermost door 8, and then opens the cap or cover 42 of the buoy, which is normally positioned with the top 90 of the housing 41 adjacent the bottom of the passage 58, as shown in dotted lines in Figure 1. The buoy is held in the cylinder by a plurality of locking members, consisting of cranks 100 secured to pointed screws 101 which pass through the casing and engage 95 the inner wall of the tube 7.

After opening the cover 42, the seaman engages the hinged prop 42' therewith to hold it open while he enters the buoy, after 100 which the door 59 is closed by the crew inside the submarine. After entering the buoy the cover 42 is closed and secured in place by the wing nuts 45 and the levers 48, the seaman being equipped with suitable oxygen equipment, not shown. When the cover 42 105 has been securely closed, the men within the submarine are advised that all is in readiness by means of the telephone system, who then retract the rod 20, open the upper valve actuated by hand wheel 35, and open the 110 lowermost valve 39 to allow the sea to enter the cylinder.

As the water rises in the chamber 7, the 115 buoy occupant retracts the screws 101 and the buoy floats within the tube. When the pressure within the cylinder 7 equals that outside the craft, door 8 is initially opened by the rod 31 in the manner hereinbefore described and by the normal pressure of the buoy thereagainst due to its buoyance. However, assuming the door 8 is frozen in place and refuses to respond to the plunger 31 and the pressure thereagainst, the buoy 120 is locked in the cylinder 7 by the pointed screws 101 and the hand wheel 84 rotated to cause the eyelet 80 to produce an opening pressure on the door.

As the door opens, the screws 101 are again 125 retracted and the buoy leaves the cylinder 7, rising to the surface under the control of 130

the hand crank 77. When the buoy reaches the surface the plug 102 may be removed from the port hole 57 and the surrounding area readily observed. If desired, the plug 91 may be removed for the discharge of rockets or other distress signals.

Oftentimes when a submarine craft becomes disabled it may be readily raised by its own power if additional air pressure can be obtained and in this event the occupant of the buoy upon opening the plug 91 signals to the craft through the telephone system and the pumps, not shown, draw in the necessary additional air through the line 88.

Assuming the craft to be hopelessly disabled, the buoy affords a means of escape for the entire crew. The first man, after leaving the buoy at the surface, closes the cover and secures it thus by means of the wrench 53, duplicates of which are carried by the entire crew. The buoy is then retracted, by winding the cable on its drum, into the cylinder 7. After the buoy has been fully retracted into the cylinder, the occupants of the craft first close valve 39 and the valve actuated by the upper hand wheel 35, cutting off all communication of the cylinder 33 with the outside water pressure. The water within the cylinder is then drained through a pet cock 103, allowing the spring 37 to retract the piston 36 and rod 31.

The door 8 is then closed by actuation of the rod 20, as the pressure on both sides thereof is equal and rod 31 is retracted, and when firmly closed the water within the cylinder 7 is removed by pumps (not shown) through the lower of two valve passages 104. As the water level within the cylinder lowers, the buoy comes with it and when it reaches the desired position viz, with the top of the buoy proper in line with the bottom of passage 58, the door 59 is opened to allow the next member of the crew to enter the buoy. It is not necessary that the entire volume of water be removed from the cylinder, but if so desired the buoy is first secured in its desired position by manipulation of the cranks 100, after which the remainder of the water may be pumped out.

The escape of the last man may readily be effected as the entire operation may be accomplished alone. In this case, the pet cock 103 is closed, the valve controlled by hand wheel 35 opened, rod 20 retracted, crank 77 and pinion 74 removed to eliminate all possible interference to the ascent of the buoy, and the door 59 and the lower sea cock 39 opened. Before the water has risen to the level of the passage 58 ample time remains to close the door 59 from the cylinder, enter the buoy and secure its cover in place. The opening of the door 8 and the escape of the buoy is then the same as before described.

Assuming now that the craft has been

disabled and rests on the bottom of the sea in such a manner that it becomes necessary to release the buoy in the direction opposite to that described, in other words the position of the buoy is reversed, the cable drum is removed and secured at the opposite end 70 of the cylinder 7, in the manner now about to be described.

The buoy is first entered at its end adjacent the passage 58, which end is now lowermost, to retract the locking screws 101 75 and permit the buoy to hang from its cable 78, and to release the inside cover locks 45 at the upper end. The cover 42 is then secured closed and the buoy lowered by the crank 77, to a position with the top of the 80 casing 41 adjacent the bottom of the passage 58. With the buoy in this position, water is permitted to enter the cylinder until the buoy floats, when the clevis 85 may be removed from the eye 80, and the plug 85 89 removed and the telephone wires disconnected at a plug 105.

After removing these connections, the now upper cover 42 is opened to permit a seaman to enter the buoy and again engage 90 the screws 101 with the cylinder 7 and secure the buoy in position. The water is then pumped out of the cylinder so that plug 91 may be removed and the telephone and air lines connected. The floor board is 95 then removed and secured to the lowermost cover.

Transferring of the cable reel to the other end of the cylinder may be readily effected as hereinbefore described, it being necessary, 100 however, to connect the telephone plug 105, clevis 85 and air hose plug 89 through opening 67 before the insertion of the reel therein. The buoy is now in position for use in identically the same manner as hereinbefore 105 described.

When the submarine with which my improved device is to be used is of exceptionally large proportions, the cylinder containing the buoy may be made in two sections, 110 each complete in itself and identical with that hereinbefore described, except that but one end opens to the sea, the other end being closed and terminating within the craft. This arrangement allows the passage along 115 the longitudinal axis of the submarine to be unobstructed and eliminates waste of valuable space.

From the foregoing description taken in connection with the accompanying drawings it will be readily obvious to those skilled in the art to which an invention of this character appertains that I have provided a means of escape from a sunken submarine which is practical and which will in no way hinder the operation of the craft and if desired the buoy may be equipped with an antenna to be raised upon reaching 125

the surface, to provide means for radio communication for the sunken submarine.

What I claim as my invention is:

1. The combination with a submarine 5 craft, of a compartment within the vessel having an opening to the interior of the craft and an opening to the exterior of the craft, closures for said openings, a buoy device normally located within the compartment and having provision for receiving an occupant, means releasably locking the closure leading to the exterior of the craft, means operable to equalize the pressure within the compartment to that without the 10 craft, and means operable by the pressure within the compartment being increased to tend to impart initial opening movement to said last-mentioned closure. 70
2. The combination with a submarine 20 craft, of a compartment within the craft having an opening to the interior of the craft and to the exterior thereof, closures for said openings, a buoy device normally located within the compartment and having provision for receiving an occupant, means releasably locking the closure leading to the exterior of the craft, means operable to equalize the pressure within the compartment to that without the craft, 25 means operable by the pressure within the compartment being increased to tend to impart initial opening movement to said last-mentioned closure, and means operable from the interior of the buoy to force the 30 last-mentioned closure open in the event the pressure operated means fails to operate said closure. 80
3. The combination with a submarine 40 craft, of a compartment within the craft having an opening to the interior and an opening to the exterior thereof, closures for said openings, a buoy device normally located within the compartment and having provisions for receiving an occupant, means 45 releasably locking the closure leading to the exterior of the craft, means operable to equalize the pressure within the compartment to that without the craft, means operable by the pressure within the compartment being 50 increased to tend to impart initial opening movement to said last-mentioned closure, and additional means for completing the initial movement of said last-mentioned closure. 90
4. The combination with a submarine 55 craft, of a compartment within the craft having an opening to the interior and an opening to the exterior thereof, closures for said openings, a buoy device normally located within the compartment and having provisions for receiving an occupant, means 60 releasably locking the closure leading to the exterior of the craft, means operable to equalize the pressure within the compartment to that without the craft, means operable by the pressure within the compartment being 65 increased to tend to impart initial opening movement to said last-mentioned closure, and means for completing the initial movement of said last-mentioned closure. 100
5. The combination with a submarine 75 craft, of a compartment within the craft having an opening to the interior and an opening to the exterior thereof, closures for 80 said openings, a buoy device normally located within the compartment and having provisions for receiving an occupant, means releasably locking the closure leading to the exterior of the craft, means permitting the entrance of sea water to the compartment to equalize the pressure therein with that without the craft, whereby the buoy floats upwardly in the compartment to abut the last-mentioned closure, and means operable 85 from the interior of the buoy device to impart an initial opening movement to the last-mentioned closure. 105
6. The combination with a submarine 90 craft, of a compartment within the craft having an opening to the interior and an opening to the exterior thereof, closures for 95 said openings, a buoy device normally located within the compartment and having provisions for receiving an occupant, means releasably locking the closure leading to the exterior of the craft, means permitting the entrance of sea water to the compartment to equalize the pressure therein with that without the craft, whereby the buoy floats upwardly in the compartment to abut the last-mentioned closure, means operable from the interior of the buoy device to impart an initial opening movement to the last-mentioned closure, and yieldable means operable 100 to complete the opening movement of said closure. 110
7. The combination with a submarine 110 craft, of a compartment within the craft having an opening to the interior and an opening to the exterior thereof, closures for 115 said openings, a buoy device normally located within the compartment and having provisions for receiving an occupant, means releasably locking the closure leading to the exterior of the craft, means permitting the entrance of sea water to the compartment to equalize the pressure therein with that without the craft, whereby the buoy floats upwardly in the compartment to engage the last-mentioned closure, means operable from the interior of the buoy device to make the same fast in the compartment with its uppermost end engaging the closure, and means projectable from the buoy device to engage the closure and impart an initial opening movement thereto. 120
8. The combination with a submarine 125 craft, of a compartment extending transversely thereacross and opening at its ends 130

- to the sea, closures for the open ends of the compartment, means permitting entrance to the compartment from the interior of the craft, a buoy normally within said compartment, and means permitting the release of said buoy from the end of the compartment which is uppermost to raise to the surface, whereby the buoy may be dispatched from the craft in the event the same becomes disabled and rests with its bottom uppermost. 45
9. The combination with a submarine craft, of a compartment extending transversely thereacross and opening at its ends to the sea, closures for the open ends of the compartment, means for permitting entrance to the compartment from the interior of the craft, a buoy normally within said compartment, a drum, means rotatably mounting the drum in either end portion of the compartment, a cable wound about said drum and having its outer end connectible with the adjacent end of the buoy, and means permitting the buoy to leave the compartment from the uppermost end. 50
10. The combination with a submarine craft, of a plurality of compartments arranged at angles with respect to each other and opening at their ends to the exterior of the craft, closures for the respective ends of the compartments, means permitting access to the interior of the compartments from the interior of the craft, and means permitting the opening of said closures. 55
11. The combination with a submarine craft, of a plurality of compartments arranged at angles with respect to each other and opening at their ends to the exterior of the craft, closures for the respective ends of the compartments, means permitting access to the interior of the respective compartments from the interior of the craft, a buoy mounted in each compartment and adapted to afford a means of escape upon disabling 60
- of the craft while submerged, and means whereby the uppermost closure of either compartment may be opened to effect the release of the buoy therein to rise to the sea's surface. 65
12. In a device of the character described, a buoy comprising an open ended cylinder, complementary nose caps closing the ends of the cylinder and means whereby said caps may be secured closed from either the interior or exterior. 70
13. In a device of the character described, a buoy comprising an open ended cylinder, complementary nose caps closing the ends of the cylinder, means whereby said caps may be secured closed from either the interior or exterior, and means within the buoy providing a platform in the lowermost cover. 75
14. In a device of the character described, a buoy, comprising an open ended cylinder, complementary nose caps closing the ends of the cylinders, means whereby said caps may be secured closed from either the interior or exterior, and means carried by each cover to permit the attachment of the cable thereto. 80
15. In a device of the character described, a buoy, comprising an open ended cylinder, complementary nose caps closing the ends of the cylinders, means whereby said caps may be secured closed from either the interior or exterior, and means permitting the connection of an air hose with either cap. 85
16. In a device of the character described, a buoy, comprising an open ended cylinder, complementary nose caps closing the ends of the cylinders, means whereby said caps may be secured closed from either the interior or exterior, and means permitting the connection of an air hose and communication means with either cap. 90

In testimony whereof I affix my signature.

AUGUST HEISE.
